UNITED STATES PATENT OFFICE.

WILHELM FALKENBERG, OF NEW YORK, N. Y., ASSIGNOR TO ALBERT WIELICH, OF NEW YORK, N. Y.

PORTABLE X-RAY APPARATUS.

Application filed June 6, 1923. Serial No. 643,744.

The object of my invention is a portable electric medical hand apparatus, in which all kinds of rays used for electro-therapeutic treatments are produced or generated including X-rays, and high frequency currents in order to allow their use with faradiation, salvanisation, galvanization, cathaphoresis, electrolysis, caustic treatments, endoscopy, light- and thermo-therapeutics 10 and also with the generation of ozone, etc.

Another object of my invention is the provision of an apparatus of this kind which in compact arrangement contains all the apparatus and circuits necessary for the above 15 named electromedical purposes.

A further object of my invention is the provision of an apparatus of this kind in which means are provided for preventing the formation of arch lights by the arrangement 20 of specially welded wolfram contacts.

A still further object of the invention is the provision of such an apparatus which is equipped with special means for allowing a vertical support of the Tesla transformer 25 adapted to receive the X-ray tube allowing a convenient folding of the same against the bottom of the apparatus casing when not in use.

These and other objects of my invention 30 will become more fully known as the description of the same proceeds, and will then be specifically pointed out in the appended claim.

In the accompanying drawings forming a 35 material part of this disclosure:

Figure 1 is a diagrammatic view illustrating the arrangement of the various instruments within the novel electro-medical hand apparatus constructed according to my invention.

Figure 2 is a top plan view of my apparatus, open.

Figure 3 is a side view of my apparatus partly in section.

In the diagrammatic illustration of the apparatus in Figure 1, 10 designates the electric socket by means of which the apparatus can be attached to any electric light circuit.

50 A switch 11 is provided in the primary circuit 12 so that according to the position of this switch, 110 or 220 voltage may be used. A selector switch 13 is located behind the switch in order to allow a selective connection of the primary circuit to a plurality

of circuits according to the specific use of the apparatus desired in the various treatments.

1. Use as X-ray apparatus.

If the apparatus shall be used for the generation of X-rays or high frequency currents, the selector is switched to make connection with contact 14.

The conductor wire 15 connected with this contact 14, leads to an induction coil 16 with an interrupter or circuit breaker 17, the wolfram contacts of which are strongly heat dispensing, and prevent the formation of an arc, in order to ensure the 65 formation of actinic sparks or rays and therewith a high efficiency of the oscillation circuit arranged parallel to the circuit breaker.

This oscillation circuit comprises the mag- 75 netically and galvanically coupled Tesla transformer 18 and condensers 19, the capacity of which can be regulated by means of the two switches 20.

The return circuit wire for the primary 80 current is designated 21, and a current meter 31 is arranged in shunt therewith.

An X-ray tube 23 is connected with the secondary circuit of the Tesla transformer 18 over a regulable spark gap 24, and is operated by means of high frequency currents 85 by means of the well known circuit. The tube is attached to two suitable holders secured to the casing of the apparatus.

The intensity of the rays is strong enough 90 to permit the making of Röntgen pictures besides permitting therapeutical treatments and also the illumination for the ascertainment of bone fractures and the discovery of foreign bodies. The apportioning and control of the ray intensity is effected by means 95 of a meter in the primary circuit and by means of the regulable capacity and regulable spark gap 24.

2. Generation of high frequency currents.

If it is desired to treat a patient with high frequency currents, the switch arrangement remains the same, the X-ray tube 23 is replaced by the suitable glass or metal electrodes which can conveniently and exchangeably be attached by means of a cable to a handle in direct connection with the circuit.

The intensity can be regulated and controlled within wide limits in the same man- 110

ner as described above with the X-ray apparatus.

3. Galvanization, cataphoresis, electrolysis.

5 If the apparatus is used for galvanization, cataphoresis and electrolysis, the selector switch 13 is operated to connect with contact 25. The current flows in this case over conductor wire 26 to a regulator resistance 10 27 and binding post 28, while the return circuit 30 is connected to binding post 29, over meter 31 by the intermediary of switch 32.

By the operation of switch 32 the sensitivity of the meter instrument 31 is increased hundred-fold, on account of the exclusion of the shunt circuit so that it allows the proper apportioning of the weak current for these treatments. Simultaneously the switch 32 constitutes a safety-device for 20 the meter instrument 31 which cannot be passed by the currents of the induction coil 16 during galvanization.

4. Caustic treatment.

25 The selector switch 13 is connected with contact 33, and the current flows over circuit 22 to binding post 34.

The cauterizing instrument (cauter) is attached to binding posts 28 and 34, and the 30 return circuit is closed over regulator resistance 27 and wires 35 and 36. The voltage can be regulated within wide limits by means of the regulator resistance.

5. Faradization.

35 The selector switch is connected with contact 37 and in this manner wire 38 in which a fixed resistance 39 is arranged, is connected with wire 36. A small sliding inductor apparatus 40 is arranged in wire 38 which is adapted for taking off the primary extra currents and secondary currents.

6. Endoscopy.

45 The selector switch 13 is connected with contact 41 so that binding posts 42 and 43 are ready for the attachment of the required instruments. The current returns over the fixed resistance 39 and wires 38 and 36. The 50 resistance prevents an overloading of the lamp.

7. Thermotherapy.

For thermotherapeutic purposes a foldable 55 parabolic mirror 44 is employed with which a heater or thermoelectric body 45 is connected which is cut into the circuit by means of a plug switch attached at 40. In this manner simultaneous a thermo- or light- 60 therapy treatment is made possible. The mirror or reflector is attached to a flexible metal covered tube allowing its movements in all directions. The mirror is removably connected by means of a bayonet attachment 65 to its tube. This tube can be held in vertical

position by a suitable post into which the tube is inserted and the reflector can then be used for sterilizing purposes if a suitable vessel is placed into the reflector.

8. Lighttherapy.

In this case the body 45 is removed by unscrewing its socket and replaced by varicolored lamps, or instead of such varicolored lamps, the margin of the mirror may be so constructed that a plurality of varicolored glasses may be attached thereto.

70 For the generation of ultraviolet rays, a mercury vapor lamp provided with a suitably threaded socket may be attached to 80 the parabolic mirror in the horizontal position of its axis.

The heater 45 serves in this case as resistance for the mercury vapor lamp and is for this purpose screwed into a socket 46 in the bottom of the apparatus casing and connected with circuit 47.

85 An automatic switch within the frame of the reflector which is actuated automatically upon the attachment of the mercury vapor lamp prevents a using of this lamp without the resistance. For this purpose the socket of the lamp is provided with a pin 48 which passes freely through a bore in contact plate 49 and during the attachment of the lamp contacts is in engagement with plate 50, and in this manner forces the current to pass the heater body 45 and to avoid wire 51 which is only used when the varicolored lamps or the heating body are to be used with the reflector on account of its connection with plate 49.

90 It will be clear that a perfect diagnosis of the physical conditions of a body can be made by making use of the actinic rays.

9. Ozone-generation.

The first position of the switch 23 is used, and a comb is placed upon the pole of the spark.

100 The arrangement of the single apparatus within the portable casing or housing 52 which is provided with a cover 53 hinged thereto in the usual manner is best illustrated in Figures 2 and 3.

105 The casing 52 and cover 53 have a suitable lock 54 and handle 55.

110 A pair of pivotally connected arms 56 secured at their outer ends to the inner walls of casing 52 and cover 53 respectively, limit the movements of the cover and hold the same in its upright position in the well known manner when the casing is open for use.

115 The meter in the primary circuit controlling the intensities of the X-ray rays is designated 57, the switch for changing from X-ray treatment to high frequency currents is designated 58, 59 is an ampere meter and 60 is a light arc meter. A frame 61 is mov-

ably held in eyes 62 secured to the bottom plate of the casing and its upstanding brackets are adapted to engage suitable openings in the bottom plate 63 of the Tesla-transformer, so that the same may either be locked in its upright position or may be rotated around an axle 64 in its bottom place to take up its position of rest within the casing indicated in dotted lines in Figure 2.

10 The instrument used for faradization is designated 65 and 66 is the instrument for galvanization.

15 The plate for meter 60 carries two pins 67, 68 for attachment of the slotted foot plate of the post for the mirror or reflector 44 which can also, when the mirror is not used, carry a knob for establishing a spark gap between its knob and knob 69 on the Tesla transformer, which is also removable

for the attachment of a comb if the instrument is used for ozonizing purposes as described.

What I claim as new, and desire to protect by Letters Patent is:

In a portable X-ray apparatus of the class described, a Tesla transformer, a casing for said transformer, including a perforated bottom plate, a U-bracket movably secured to the bottom plate of said apparatus and adapted to engage with its free arms the perforations in said bottom plate, and a pin 25 in said bottom plate journaled within the apparatus for allowing a folding of said transformer against the bottom of said apparatus when not in use.

30 In testimony whereof I have affixed my signature.

35 WILHELM FALKENBERG.
